UNITED STATES PATENT OFFICE.

SAMUEL JOSEPH BLUMENTHAL, OF BROOKLYN, NEW YORK.

SLEEVE-VALVE ENGINE.

Application filed April 6, 1926. Serial No. 100,041.

The present invention relates to internal combustion engines of the kind in which a sleeve is employed to control the opening and closing of the valve ports of the engine.

Engines have been constructed provided with one or two such sleeves arranged between the cylinder wall and piston and provided with independent operating means. In such engines, however, the ports are generally arranged in the usual positions, toward the head of the cylinder, or in the case of two-cycle engines toward the bottom of the cylinder.

It will be understood that when the valve ports are arranged in a limited area of the cylinder, numerous difficulties are met with, such as restriction of valve passages making it difficult in the case of high speed engines to inject sufficient fuel into the cylinder in the very short space of time during which the inlet valve is open, and excessive heating of the exhaust port owing to all the hot gases being expelled through the same port, this localized heating also tending to cause warping of the cylinder and sleeves and burning of the exhaust valve.

In sleeve valve engines employing the usual two sleeves, further difficulties are met with owing to the necessity for extremely accurate finishing of the sleeves and the difficulty of maintaining a sufficient flow of lubricant between them owing to excessive local heating. These difficulties are of course much aggravated in the case of two-stroke engines in which engines the cylinder is practically continuously full of burning gas with the result that it is almost impossible to avoid over heating of these engines except under the most favorable conditions, this over heating resulting in the rapid destruction of sparking plugs and exhaust valves and rapid wear of the cylinder. A still further disadvantage of the sleeve valve engines in which the sleeves are arranged between the cylinder and piston is that the sleeves are necessarily of very thin metal and relatively little mechanical strength with the result that any seizing of the sleeve due to unequal expansion or seizing due to burning of the lubricant between the sleeves or any other cause, results in destruction or very severe injury of the sleeves and their operating mechanism.

The general object of the invention is to provide a sleeve valve construction which will at once avoid the draw-backs of the

known type of sleeve valve engines and also improve the performance characteristics of internal combustion engines.

A further object of the invention is to provide an engine in which the valve mechanism is considerably simplified.

A still further object of the invention is to provide both four stroke and two-stroke engines having sleeve controlled ports of a novel character.

The invention specifically consists in the provision of an internal combustion engine having ports arranged substantially throughout the working face of the cylinder wall, these ports being controlled by a simple and rugged sleeve valve carried by the piston.

Further objects and features of the invention will hereinafter appear in the appended specification.

In the specification and drawings various forms of engine constructed according to my invention are illustrated and described; but these constructions of engines are chosen merely by way of example and are not intended in any way to delimit the scope of the invention which is clearly defined in the appended claims.

Numerous modifications of the invention will readily occur to those skilled in the art and the constructions of engine described have been chosen merely to illustrate the application of the invention to types of engine in general use.

In the drawings—

Figure 1 is a view in elevation and Figure 2 in cross section of a two-stroke engine embodying the features of my invention;

Figure 3 is an elevation partly in section showing the application of my invention to a four-cycle internal combustion engine;

Figure 4 is a detail view showing the cam construction and operating means for moving the extra sleeve employed in the engine of Fig. 3.

Figure 5 is a detail view showing a preferred construction of pressure retaining ring employed to maintain a gas tight seal between the sleeve and the cylinder wall.

Figures 6, 7 and 8 are fragmental views of the developed cylinder and sleeve surfaces of the engines shown in Figs. 1 and 2 showing the relative position of the ports and sleeves at the important points in the cycle of operation;

Figure 9 is a similar view showing the arrangement of the ports of the sleeve and cylinder wall of an engine construction in which a single rotatable sleeve is employed as shown in Fig. 11;

Figure 10 shows, partly in section, the adaption of my invention to an air plane engine, the inlet port being controlled by an additional sleeve;

10 Figure 11 shows, partly in section, a four-stroke engine adapted for standard use in automobiles and the like;

15 Figure 12 is a detail view showing the operating means for the sleeve of the engine shown in Fig. 11.

Similar numerals indicate similar parts in the various views.

Referring to Figs. 1 and 2 1 indicates the cylinder wall and 2 the water jacket cast integral with said cylinder wall in the usual manner. 3 indicates a detachable cylinder head provided with cooling water channels 4, 4^a being the point of connection to the radiator. Owing to the depth of the cylinder head, the water circulation is preferably effected by force pump but in order to simplify the drawings the cooling system is not illustrated since this may be of any well known kind. Preferably cooling water enters toward the bottom of the water jacket and leaves at the cylinder head.

In the two-stroke engine illustrated in Figs. 1 and 2 a single sleeve 5 is employed to control the opening of all valve ports, this sleeve in the construction of engine illustrated being merely a tube mounted by screws upon the piston 6. The exhaust ports 7 of the engine are formed in the cylinder wall in four equi-distantly spaced series 40 each arranged on a spiral line throughout the height and extending round one-quarter of the circumference of the cylinder. Further valve openings 8 are provided for the introduction of combustible mixture, and 45 openings 9 for the entry of the scavenging blast compressed in the crank case by the method usual in this type of engine. Corresponding openings 7^a adapted to register with the exhaust port openings 7, 8^a adapted 50 to register with the combustible port 8 and 9^a adapted to register with the scavenging air ports 9 are formed in the sleeve 5.

While various valve settings may be arranged for, a particular valve setting will 55 be given hereafter merely by way of example.

The spacing of the openings in the sleeve and cylinder wall is such that the exhaust ports begin to open 45° before lower dead center, are full open at lower dead center and shut at 45° after lower dead center. The scavenging air ports open 22½° before lower dead center and shut at 22½° after lower dead center. The combustible mixture port 60 opens 45° after lower dead center and shuts

90° after lower dead center, ignition of the charge taking place at substantially the top dead center. An opening 10 is formed in the cylinder wall into which the spark plug is screwed and a corresponding opening, 10^a, 70 is formed in the sleeve 5 and adapted to expose said opening 10.

It will be at once realized that the valve area provided by the construction just described is many times larger than that possible in the known type of engine either 75 puppet or sleeve valve and this results in a much better performance than that of the engine of known type for the following reasons:

The exhaust is free to leave throughout the height of the cylinder through a very much larger port area. This not only makes for a complete exhaustion of the cylinders in a much shorter length of time but also for 85 more equal temperature distribution throughout the cylinder wall while the equally distributed scavenging air is calculated to act effectively to cause more thorough expulsion of the burned gases while the spark plug is 90 protected from all but a small portion of the heat of the explosion. As a result of the thorough expulsion of the burned gases and free entry of the scavenging air from 95 all sides of the cylinder, the exhaust ports close on pure air into which a charge of very rich gas is injected, all ports subsequently closing during the remainder of the compression stroke until the opening of the chamber in which the spark plug is mounted. On the downward movement of the sleeve, the inlet or mixture port 8 is of course 100 opened but by the use of a puppet valve 11 controlling the inlet of the mixture, the combustion chamber is maintained closed. This 105 puppet valve construction will now be described:

The function of the mixture chamber 12 is to supply a quantity of very rich mixture and for this reason a special construction is 110 illustrated calculated to supply a mixture of the character desired. The chamber comprises two halves of which the lower is mounted by studs 13 upon the water jacket in registration with the mixture inlet pipe 115 14, while the upper half is mounted by any suitable means upon the lower half as, for instance by a plurality of screws 15. The lower half is formed to provide a connection 16 for the high pressure air supply and to receive the valve seat 17. The valve seat is formed in a separate member 18 of symmetrical shape and is positioned relatively to the lower half of the valve casing by being screwed down upon the upstanding threaded flange 19 of said lower part. The member 18 is formed with a flange 19^a adapted to abut against the top flange of the lower half of the valve casing and is placed 120 in position before the drilling of the holes 130

for the screws holding the two halves of the valve casing together, sufficient play being provided for in the apertures thus formed in the flange 19 to enable the valve casing to be taken apart and the valve seat readily removed from or placed in position without interfering with the screwing up of the two halves of the casing. The member 18 also comprises a seat 20 adapted to receive a substantially conical member formed of several layers of wire gauze 21 held in position by a frame 21 positioned in a recess 22 turned in the inner face of the member 18. Apertures 23 are formed around the outer periphery of the member 18 and a dependent skirt 23^a is formed on said member to fit over an upstanding flange 24 formed on the bottom of the lower half of the valve casing. An aperture 25 enables air from the pipe 26 to pass through the bottom of the lower half of the casing between the skirt 23^a and flange 24 passing through and vaporizing any gasoline that might have collected in the bottom of the chamber. The upper part of the casing comprises a gasoline feeding pipe 27 provided with holes through which gasoline is adapted to be squirted on to the wire gauze 21. The upper part of the valve casing also provides a housing for the spring 29 serving to hold the puppet valve 11 on its seat. This spring bears against a disc 30 seated on an upstanding bearing 31 supported by a spider 32 formed integral with the member 18 while at its upper end the spring bears against a dished washer held in position by a key passing through the valve stem. A tappet plate 34 is mounted upon the threaded end of the valve stem and serves to enable any necessary adjustment for wear to be made by being screwed up or down said valve stem. The valve is operated by valve mechanism of a known kind including an operating lever 35 pivoted at 36 on a bearing piece 37 bolted to the cylinder head and also serving to guide the valve rod 38, the valve rod being actuated by the cam 39 carried on the cam shaft 40 driven at engine speed by the chain 41 running on chain wheels carried at the forward end of the engine shaft. Gasoline is supplied to the valve chamber by means of a plunger operated pump operated by the valve rod by means of a pin 42 mounted on this rod engaging a lever 42 one end of which engages a plunger 43^a of a small pump and the other end of which is mounted on an adjustable abutment by means of which the setting of the pump delivery limits may be adjusted. The richness of the mixture and the amount thereof delivered past the valve 11 is governed by cock 43 in the high pressure pipe 44 which serves to by pass the gasoline when it is desired to keep down the amount delivered to the mixing chamber 12.

The exhaust is carried away by the exhaust manifold arranged to surround the cylinder but is not illustrated since no particular novelty resides therein, this manifold being of any form suitable for the purpose and being bolted to the exhaust outlets 47, 48, 49. For instance a manifold cast in two halves adapted to be bolted to the exhaust outlets would serve the purpose. High pressure air may be delivered by any suitable means, in the construction illustrated by means of a small high speed air compressor 52 chain driven from the cam shaft 40. Any suitable means to prevent excessive pressure in the pipe line when the valve 46 is set to deliver a small quantity of air to the valve casing may be provided, for instance the shutting down of the pipe line by said valve could be arranged to open an orifice venting the compressed air to the atmosphere. The scavenging air is compressed in the crank case in the manner usual in two stroke engines, air being sucked into the crank case on the upstroke of the piston 6 through the breather valve 50 and delivered through a conduit to a circular inlet conduit communicating with the scavenging ports in the cylinder wall. The breather valve comprises a lightplate 53 guided on a tubular stem 54, having fins 55 projecting therefrom and engaging with the sides of the air pipe 56. Air, on the upstroke of the piston is sucked through the orifices 57 and between the plate and packing ring 59 and through the orifice 60 into the air pipe, while on the down-stroke of the piston the increased pressure of the air is sufficient to raise the light plate 53 into contact with the ring 59, sealing the crank case. The weight of the moving parts, light as they are, may be further reduced by a light spring 33 arranged to bear against the under side of said plate. Any other suitable form of valve admitting air during the upstroke of the piston may of course be provided.

In Figure 3 which shows the adaption of my invention to an engine of the four-stroke cycle, it will be noted that an additional sleeve 61 is employed. This additional sleeve is of course necessitated by the need of keeping closed the exhaust ports 62^a of the engine during the compression and explosion strokes. The sleeve 61 is moved first in one direction to open the exhaust ports 62^a and then in the opposite direction to close the exhaust ports. A separate sleeve 61^a may be utilized to control the inlet ports 62 which are shown as interrupted by a solid portion serving to reinforce the sleeve (Fig. 3), but of course it will be understood that with a different arrangement of ports, for instance as arranged in Fig. 11, both inlet and exhaust ports could be controlled by a single additional sleeve. Any

suitable mechanism may be employed to operate the sleeves, that illustrated in Fig. 3 is oscillated by means comprising a cam 63 mounted on a half-time shaft 64 which is driven in any suitable way from the crank shaft, co-operating with a rock shaft 65. A valve operating arm 66 is mounted fast upon the rock shaft 65 and extends downwardly and engages by a slot 67 in its lower end a pin 68 projecting from a slide 69. The sleeve 61 is supported in position in the cylinder by means of the positioning ring 70 detachably secured to the cylinder wall, as for instance by being screwed thereto. The slide 69 is supported by an extension 71 of the crank case and reciprocates in a slot formed in the lower half of a portion of the positioning ring 70. It will be realized that only a small portion of the ring need be removed in order to enable the slide to underlie the additional sleeve in position to engage said sleeve by means of a finger piece 72 carried by said slide and projecting into a recess 73 formed in the strengthening flange 75 arranged around the lower extremity of the sleeve 61. The finger piece 72 engages the strengthening flange by means of a roller 72'. The actuating arm 66 engages the cam 63 through a roller 76 and is pressed against said cam by means of a tension spring 77 connected at one end to an arm 78 fast on the shaft 65 and at the other end to a stud screwed into the water jacket. It will be realized that this construction causes positive actuation of the slide in both directions and oscillation of the sleeve 61, the cam 63 serving to move the slide in one direction and the spring 77 serving to move the slide in the opposite direction. In Fig. 3 a single cylinder construction is shown by way of example, but this construction of engine is readily adaptable to block construction, each cylinder unit being provided with a separate operating slide of the kind described and cam slide actuating means of the kind described, the cams being mounted on a common cam shaft 64 extending along the several cylinders. In Fig. 3 this cam shaft has been arranged parallel to the diameter of the crank case merely for purposes of illustration.

The separate sleeve 61^a shown in Fig. 3 may be operated in any suitable manner, for instance in a block construction by a separate cam shaft and slide operating arms. These operating means have not been shown since the adaption of the construction described for operation of the sleeve 61 to the sleeve 61^a could be readily effected by those skilled in engine construction. The cam controlled to and fro movement of the sleeves has been illustrated and described since a larger number of ports may be then utilized and the opening and shutting movements made to occur in a minimum time, af-

fording a maximum period during which the ports remain open, whereas in a continuous rotational movement the opening and closing of the ports would occur uniformly and full opening would, therefore, be relatively of short duration, though possibly by making the ports in the cylinder wider than those in the sleeve or vice versa a satisfactory opening of the ports for a particular engine may be obtainable.

In Fig. 5 is illustrated a preferred form of sleeve which may be utilized in any of the constructions of engine herein described. The feature of this sleeve construction is that the gas retaining seal between the sleeve and cylinder wall or surface of another sleeve is improved. This effect is obtained by forming the sleeve with raised portions. Owing to the relatively deep ports preferably utilized, it would be generally preferable to cast the sleeve with these raised portions, though, of course, in certain cases it might be preferred to use a deep ring fitting in a groove turned in the sleeve in the manner usual with the relatively narrow piston rings found in gas engines. While the raised portions may be formed separately, I prefer to employ the construction illustrated in Fig. 5 in which the raised portions are formed as a continuous ring, since the upper and lower parts 79 of the raised portion acting to seal the top and bottom of the ports which portions are continuous between ports on the same horizontal line, and serve as a pressure retaining ring preventing passage of the gases from the cylinder space into the crank case. The raised portion between the parts 80 acting to seal the vertical edges of the ports may be reduced in thickness to provide a thickness of metal uniform with those parts of the sleeve not provided with the raised portions or sealing rings.

In Figs. 6, 7 and 8 full lines indicate the ports formed in the sleeve of the engine shown in the construction of engine in Figs. 1, 2 and 10, while dotted lines indicate the ports formed in the cylinder wall above the level of the top of the cylinder in the particular position shown in the respective figures. Three positions of the sleeve are shown in order to make clear the opening movement of the ports.

In Fig. 6 which shows the position of the sleeve at the moment of firing, all ports are closed except that the opening 10 (Fig. 2) is exposing the spark plug points. In this figure a fragmental portion of the sleeve is shown extending from the plug port 10 toward the center of the cylinder.

In Fig. 7 is shown the port opening at lower dead center, the figure showing a fragment of the sleeve taken on the center line of the view shown in Fig. 2. It will be observed that both the scavenging ports 9'

and exhaust ports 7' are fully open. Since the exhaust ports 7' commence to open $22\frac{1}{2}^{\circ}$ before the scavenging ports 9', the pressure in the cylinder will be much reduced before the opening of the scavenging ports and the entry of the air compressed in the crank case.

In Fig. 8 is shown the position of the ports when the crank pin center reaches a point 45° after lower dead center. In this position it will be seen that the exhaust ports 7' have just closed while the ports for the inlet of the rich mixture are about to open. These ports are so proportioned as to remain open approximately during the movement of the crank pin center through a further 45° after which the inlet port 8' remains closed. At approximately top dead center the firing point is reached.

In Fig. 9 is shown an enlarged view of the port arrangement of the engine construction shown in Fig. 11, i. e. one in which a single rotating sleeve is employed to control both inlet and exhaust ports. It will be seen that the ports in the sleeve are arranged so that inlet and exhaust lie in the same vertical line, while in the cylinder wall the exhaust ports are placed on a vertical line spaced sufficiently from that of the inlet port to enable the sleeve ports to rest on solid metal during the compression and explosion strokes, the cam operating the sleeve as shown in Fig. 12 being designed to move the sleeve two port spaces in one direction; for instance to the exhaust open position and then allowing the sleeve to return one space to all ports closed position and then through a further space to inlet open position.

In Fig. 10 a light form of two-stroke engine embodying my invention is shown. For the sake of lightness, only the working face of the cylinder is water cooled by a jacket of minimum proportions, while the head of the cylinder is cooled by a water jacket connected to that of the cylinder by means of a pipe 104. The upstanding member of the cylinder head provided to house the sleeve 83 when in raised position is provided with cooling fins 105 to aid in radiating whatever heat may reach this cylinder head by conduction. It will be seen that the general port arrangement of the engine shown in Figs. 1 and 2 is retained, but that the puppet valve acting to close the rich mixture inlet during the working stroke is controlled by a light sleeve valve 8', to accommodate which a portion of the cylinder is formed of greater diameter than the external diameter of the main sleeve valve. The sleeve valve 8' may be operated by any suitable means. A convenient method of accomplishing this movement may be as illustrated by means of the cam 84 on the cam shaft 82 and lever 85. The end 86 of this lever is formed to receive a small sliding block 87 which

receives a pin passing through a vertical slot 88 in the cylinder and screwing into the sleeve 81 which should be long enough to close, or be furnished with an extension closing, the slot 88 in order to enable the crank case to be used as a compression chamber. Since the drawing is intended merely for purposes of illustration, the proportions are not to be taken as accurately showing the proportion of the engine.

In Fig. 11 a form of engine is shown having the characteristic feature of my invention, namely a series of ports extending throughout the height of the working face of the cylinder, but in place of a reciprocating sleeve or a reciprocating sleeve combined with a rotating or revolving sleeve, a single revolving sleeve is arranged to control all the valve ports. The engine is designed to work on the 4-stroke cycle and is of medium weight, the general layout being one suitable for standard production such as for use in the automobile trade. It will be observed that the construction provides a neat and simple engine of sturdy design. A single sleeve 89 is supported on a ring 90 which may be provided with a thread 91 engaging the thread turned in the lower end of the cylinder casting. Actuation of the sleeve in the construction illustrated may be simply and effectively obtained by means of a cam 92 mounted on a cam shaft 93 and reciprocating rod 94, Fig. 12. Rod 94 may be reciprocated direct from the cam, but preferably as shown through the intermediary of a lever 95 serving to amplify the throw of the cam. A pin 96 projects from the rod 95 and engages in a slot in a lug 97 (Fig. 12) screwed or otherwise fastened to the sleeve 89. In the construction shown, the piston 98 is of the slipper type, the cut-away portion enabling a shorter sleeve to be utilized in that the recess so formed provides a clearance for the inner end of the lug 97. 99 indicates a carburetter of any ordinary or suitable type, and 100 a common exhaust manifold for the cylinders. In this form of engine the exhaust ports open into a common exhaust passage 101 and the inlet ports 8 communicate with a common inlet conduit 102, 103 being a water jacket surrounding and enclosing the whole upper portion of the cylinder. By reference to the port diagram in Fig. 9, it will be observed that the exhaust ports occupy roughly one-third of the surface of the cylinder wall, leaving roughly rather less than two-thirds of the wall to be cooled.

Throughout the various constructions, it is pointed out that only approximate proportions are shown and no attempt to provide accurate working drawings has been made. By this statement I intend to make clear that the drawings are designed to illustrate various embodiments of my invention in

engines of widely different type and in order to show the wide applicability of my invention the engines chosen are one suitable for heavy stationary work (Figs. 1 and 2); another of medium weight (Figs. 3 and 4); a light weight high speed engine suitable for air planes or racing cars (Fig. 10), and a medium duty, simple design suitable for use in automobiles (Fig. 11).

- 10 Owing to the port construction which comprises apertures adapted to overlie one another, carbon can be removed from the top of the cylinder or combustion space very readily by inserting scraper tools through 15 said apertures for instance by unscrewing the ignition plug of Fig. 2. Many ways of carrying out this arrangement will occur to those familiar with engine assembly, for instance in the form of engine shown in 20 Fig. 10, this cover plate might be arranged on the exhaust conduit 106 and register with an exhaust opening through the cylinder wall.

As before pointed out the forms of engine 25 illustrated in the drawings are merely given by way of example and are in no way limitative of my invention which is clearly defined by the scope of the appended claims.

What I claim is:—

- 30 1. A sleeve valve engine comprising a cylinder, conduits for the passage of working fluid communicating with the interior of said cylinder through a plurality of ports arranged at spaced points throughout both 35 the height and circumference of the face of that portion of said cylinder in which combustion occurs, a piston within said cylinder, sleeve valve means carried by the piston and provided with openings adapted to register with said ports in the cylinder wall at predetermined points in the travel of the piston, and means for supplying working fluid to 40 said cylinder.

- 45 2. A sleeve valve engine comprising a cylinder, conduits for the passage of working fluid communicating with the interior of said cylinder through a plurality of ports throughout the height and circumference of the face of that portion of said cylinder in 50 which combustion occurs, a piston within said cylinder, sleeve valve means carried by the piston and provided with openings adapted to register with said ports in the cylinder wall at predetermined points in the travel of the piston, said ports comprising 55 exhaust and inlet openings, and means for supplying working fluid to said cylinder.

- 60 3. A sleeve valve engine comprising a cylinder, conduits for the passage of working fluid communicating with the interior of said cylinder through a plurality of ports arranged throughout the height and circumference of the face of that portion of said cylinder in which combustion occurs, a piston within 65 said cylinder, sleeve valve means

carried by the piston and provided with openings adapted to register with said ports in the cylinder wall at predetermined points in the travel of the piston, having the exhaust ports arranged substantially throughout the height and circumference of the working face of the cylinder, and means for supplying working fluid to said cylinder.

4. A sleeve valve engine comprising a cylinder, conduits for the passage of working fluid communicating with the interior of said cylinder through a plurality of ports arranged throughout the height and circumference of the face of that portion of said cylinder in which combustion occurs, 70 a piston within said cylinder, sleeve valve means carried by the piston, and provided with openings adapted to register with said ports in the cylinder wall at predetermined points in the travel of the piston, said ports comprising exhaust and inlet ports and ports for the admission of additional gaseous medium, and means for supplying working fluid to said cylinder.

5. A sleeve valve engine comprising a cylinder, conduits for the passage of working fluid communicating with the interior of said cylinder through a plurality of ports throughout the height and circumference of the face of that portion of said cylinder in 90 which combustion occurs, a piston within said cylinder, sleeve valve means carried by the piston and provided with openings adapted to register with said ports in the cylinder wall at predetermined points in the 95 travel of the piston, and further valve means cooperating with said sleeve valve to control the supply of carburetted mixture to the cylinder through port openings intermediate the top and bottom of the cylinder 100 space in which combustion occurs and means for supplying working fluid to said cylinder.

6. A sleeve valve engine as claimed in claim 1, having means for mixing said air with combustible material comprising a valve casing divided into an upper and power portion, the lower portion serving to house a detachable valve seating unit, said detachable valve seating being provided with a frame acting to support a member of porous material upon which liquid fuel is adapted to be sprayed, means actuated by the engine for spraying the liquid fuel upon the said porous material, the gaseous medium entering the cylinder being caused to pass through said saturated porous material and thereby form a rich explosive mixture.

7. A sleeve valve engine comprising a cylinder, conduits for the passage of working fluid communicating with the interior of said cylinder through a plurality of ports throughout the height and circumference of the face of that portion of said cylinder in which combustion occurs, a piston within 120

5 said cylinder, sleeve valve means carried by the piston and provided with openings adapted to register with said ports in the cylinder wall at predetermined points in the travel of the piston, said sleeve being constructed to form a substantially gas tight seal between said sleeve and the cylinder wall, said gas tight seal extending around the periphery of the openings in the sleeve 10 and means for supplying working fluid to said cylinder.

15 8. A sleeve valve engine, comprising a cylinder, a plurality of ports for the introduction of scavenging air formed in the cylinder wall toward the top of the cylinder, exhaust ports arranged symmetrically in a plurality of series arranged at successive points in the height of the working face of the cylinder, said points extending from the upper 20 end of the cylinder space toward the bottom thereof, inlet means for the carburetted

mixture formed in the cylinder wall intermediate the top and bottom of the face of the portion of the cylinder in which combustion occurs, apertured sleeve valve means 25 carried by the piston, said apertures being arranged to register with all of said ports in the cylinder wall at predetermined points in the travel of the piston and further valve means cooperating with said sleeve valve 30 to control the supply of carburetted mixture to the cylinder, means for supplying working fluid to said cylinder, and common manifold means for collecting the exhaust from a plurality of said exhaust ports arranged 35 at different points in the height of the face of that portion of the cylinder in which combustion occurs.

In testimony whereof I affix my signature.

SAMUEL JOSEPH BLUMENTHAL.
